UNITED STATES PATENT OFFICE.

JOHN P. BADENHAUSEN, OF PHILADELPHIA, PENNSYLVANIA.

STEAM-GENERATING SYSTEM FOR LOCOMOTIVES.

1,404,420.

Specification of Letters Patent. Patented Jan. 24, 1922.

Application filed April 30, 1918. Serial No. 293,657.

To all whom it may concern:

Be it known that I, JOHN P. BADENHAUSEN, a citizen of the United States, and a resident of the city of Philadelphia, county of Philadelphia, State of Pennsylvania, have invented certain new and useful Improvements in Steam-Generating Systems for Locomotives, of which the following is a specification, reference being had to 10 the accompanying drawings, forming a part hereof.

My invention relates to a steam generating system of the water tube type adapted to be employed in a locomotive, and more particularly, relates to a generator comprising a water tube boiler section and an economizer or preheater section arranged to receive and absorb the heat of the products of combustion after passing from the water tube boiler section and prior to escaping through the smoke stack.

My invention comprehends the idea of using a water tube boiler located in the furnace portion of the locomotive where a very rapid generation of steam may be secured and an economizer or preheater section in the forward portion of the locomotive comprising auxiliary steam and water drums connected by a set of tubes located in the path of the hot gases flowing from the boiler section to the smoke stack, whereby in addition to the generation of steam secured in the water tube boiler section, I am also enabled to absorb additional heat from the hot gases which otherwise would be totally lost. In this manner the water in the auxiliary system may be heated very much in the same manner as water is usually heated in an economizer. The water portion of the auxiliary system so heated is adapted to supply the lower water drum of the boiler section where the water in the same may be rapidly generated into steam as aforesaid. The upper drum of the auxiliary system, on the other hand, contains the steam generated in the tubes of the boiler proper and in the tubes of the auxiliary system, the generation in the latter being affected by the contact of the hot gases with the last mentioned tubes as they pass from the boiler section to the smoke stack. In this manner I am enabled to provide in a locomotive a generator comprising a water tube boiler, an economizer and an auxiliary steam generating means,

the latter two being combined into a single 55 unitary device.

My invention, therefore, has for its object the provision, in a locomotive, of a generator comprising a water tube boiler combined with supplementary heating means 60 to economize heat from the escaping hot gases. Another object is to provide the steam generating plant with greatly increased heating surface and consequently to considerably increase the capacity and the 65 economy thereof. A still further object is to materially reduce the weight of the heating plant.

Such further objects and advantages as may arise from my improved structure will 70 more fully appear from the following specification.

In the drawings in which I have shown the preferred form or embodiment of my invention;

Fig. 1 is a longitudinal vertical sectional view through a locomotive including my invention;

Fig. 2 is a transverse section on line 2—2 of Fig. 1;

Fig. 3 is a transverse section of the economizing unit taken on the line 3—3 of Fig. 1; and,

Fig. 4 is a top plan view of the mud ring and grate with a portion shown in broken 85 section.

Referring now more particularly to the drawing, I have shown in general a locomotive 1 of the usual outside structure the same being provided at the rear portion thereof 90 with a water tube boiler 2. This boiler comprises a lower water drum 3, an upper, or intermediate, water drum 4 and a steam drum 5, all of which are located in transverse relation to the length of the locomotive 95 and in triangular arrangement. The water drums 3 and 4 are connected by a bank of pipes or tubes 6, these pipes being located in an inclined position immediately over the fire and adapted to receive the direct contact of the flames in the fire box. The upper or intermediate water drum 4 and the steam drum 5 are also connected by a bank of pipes or tubes 7 in inclined position and are adapted to be contacted with the flames as they 100 pass from the first bank of pipes 6 and are deflected by the fire bridge or wall 8 to the upper portion of the boiler space. The

lower water drum 3 and the steam drum 5 are also connected by a third bank of pipes or tubes 9, arranged generally in a vertical position, adapted to be contacted with the 5 hot gases after the same have passed by the fire bridge and through the pipes 7 prior to such gases passing forward to the other end of the locomotive. In this arrangement the bank of tubes 6, 7 and 9 are respectively 10 successively contacted by the burning gases prior to their escape to the economizer section.

The fire box instead of being of the usual type, is surrounded by a plurality of tubes 15 of which the tubes 10 and 10' form the side walls of the fire box, tubes 11 the rear wall and tubes 12 the front wall. All of these tubes, namely, 10, 10', 11 and 12, are connected at their lower ends with the rectangular hollow mud ring 13. The rear short tubes 11 are connected at the upper ends thereof to the lower water drum 3 while of the side tubes 10 and 10' the same are respectively connected at their upper ends to 25 the drums 4 and 5. The front tubes 12, however, all lead from the mud ring 13 to the upper or intermediate water drum 4.

The mud ring, it will be noted, is supported in any suitable manner, as by the 30 cross pieces 14 and 15 and has included therein the usual set of grate bars 16 suitably supported upon bracket members 17 and 18 secured to said cross pieces and to the sides of the locomotive.

35 The above structure constitutes the boiler portion of the locomotive where the primary generation of steam occurs and where the combustible constituents are undergoing their most intense action in giving off heat 40 to the several tubes presented in the path thereof.

At the forward portion of the locomotive between the boiler portion described above and the smoke stack 1', I have arranged a 45 device which is in the nature of a combination steam generating and economizing means and comprises a steam drum 19 and a water drum 20, both arranged longitudinally of the locomotive with the steam drum 50 located at the top and the water drum at the bottom and connected at the ends thereof respectively with the steam drum 5 and the lower water drum 3. The steam drums 5 and 19 therefore form a T-shaped drum 55 with the leg of the T extending longitudinally along the top of the locomotive between the boiler and the smoke stack. The water drums 3 and 20 form a similar structure and are located below and parallel to 60 the other.

Both of the drums 19 and 20 are connected with a plurality of tubes 21 so located that the same shall be contacted by the hot gases as the latter pass from the boiler to the forward portion of the locomotive where the 65

smoke stack is located. The normal water level in the drums 5 and 19 is above the upper ends of these tubes in order that proper circulation may be affected therein.

The steam drum 19 is provided internally 70 thereof with a suspending bracket 22 utilized to support the steam conduit 23 with its inner end thereof upwardly bent to receive the steam from said drum and to convey the same to the throttle 24 suitably secured to the outside forward end of the steam drum 19. From this throttle a pair of steam conduits 25 may lead to the respective sides of the locomotive to the cylinders 75 26 located at both sides of the locomotive. 80

It will be noted that both the boiler and the economizer or preheater section are covered or surrounded by a protective wall 27, of any suitable material, which is further covered by heat insulating material 28 completely surrounding said wall 27 to incase or enclose said boiler and economizer or pre-heater section. 85

It will be noted that at the rear of the fire box or furnace a space is provided opposite the fire door 29 by omission of a few tubes in the front wall comprising tubes 12 to permit the introduction of fuel within the furnace. 90

In operation the fuel is introduced 95 through the fire door 9 into the fire box or furnace upon the grate 16 where combustion occurs, the hot gases arising therefrom passing upwardly through the several banks of pipes 6, 7 and 9, delivering a portion of the 100 heat thereof to said pipes and the water contained therein in generating the same into steam at a comparatively rapid rate. The flames and hot gases are deflected by the bridge wall 8 to direct the flames upwardly 105 through the second bank of pipes 7 to also further deliver up heat thereto in further generation of steam from the fluid contained therein. As the gases are deflected from the upper wall 30 of the boiler, the same 110 will be caused to pass forwardly through the third bank of pipes 9, where a still further generation of steam, from the water contained therein, may occur.

At this point, the gases, the heat of which 115 has not been completely absorbed, flow among the large number of tubes 21 connected between the water drum 20 and the steam drum 19 and the further absorption of heat from said gases is utilized to heat the 120 water included in said tubes to partially generate steam therefrom which passes to the steam drum 19 and to also heat the water therein as well as in the drum 20. The water so heated will be adapted to flow to 125 the lower water drum 3 of the boiler for further heating in the furnace for generation into steam. In this way, this portion of the economizer or preheater section acts similarly to economizers in general use. The 130

feed water may be admitted at any point desired in the lower part of the steam system, as by a conduit 31 leading preferably into the end of the drum 20, the conduit being 5 provided with any suitable type of check valve 32, if desired.

It will, therefore, be observed from the above that the drums 19 and 20 and the tubes 21 constitute a device having the combined function of preheating water in the same manner as in an economizer and converting water into steam. In this manner, I have been able to considerably increase the efficiency of the water tube boiler as well as 10 maintaining a capacity that will meet the demands required of a boiler for locomotive service with the added advantage of the very rapid generation of steam by the use of a water tube boiler.

20 While I have shown but one form of device illustrating my invention, it is to be understood, however, that any other embodiment may be utilized to carry out the idea of the same without departing from the 25 spirit of my invention nor from the scope of the appended claims.

Having thus described my invention, I claim and desire to protect by Letters Patent:

30 1. A steam generating system for locomotives, consisting of a water tube boiler comprising a water drum, an intermediate drum and a steam drum in triangular relation, a plurality of tubes connecting said drums, a 35 furnace provided with walls constituted of tubes, a mud ring connected to said tubes, the other ends of said tubes being connected to said drums and a supplementary steam generating and economizing water tube section comprising steam and water drums 40 connected to said first mentioned steam and water drums.

2. A steam generating system for locomotives, consisting of a water tube boiler comprising transverse water, intermediate and steam drums, tubes connecting said drums, an economizer section comprising spaced water and steam drums respectively connected to said water drum and said steam 45 drum of said boiler and a plurality of tubes connecting said steam drum and water drum

of said economizer section and located in the path of the hot gases passing from said boiler to the smoke stack of said locomotive.

3. A steam generating system for locomotives, comprising a lower transverse drum, an upper transverse drum spaced from said lower drum, and an intermediate transverse drum spaced from said lower and upper drums, a bank of tubes connecting said lower 55 and intermediate drums, a second bank of tubes connecting said intermediate and upper drums and a third bank of tubes connecting said upper and lower drums, a combustion furnace provided with walls constituted of tubes, a mud ring at the lower portion of said furnace, said drums and said mud ring being connected by said tubes and an economizer element located adjacent to and connected to said boiler.

4. A steam generating system for locomotives, consisting of a water tube boiler comprising transverse water, intermediate and steam drums arranged in triangular relation, a plurality of tubes connecting said 75 drums, a furnace provided with walls constituted of tubes, a mud ring connected to said tubes, the other ends of said tubes being connected to said drums, longitudinally disposed supplementary steam and water drums 80 connected at an end thereof to intermediate portions of said first mentioned steam and water drums respectively and a plurality of water tubes connecting said supplementary steam and water drums.

5. A steam generating system for locomotives, consisting of the combination of a water tube boiler and a heat absorbing section connected thereto and adapted to heat water supplied to said boiler, said combined 90 boiler and section comprising an upper T-shaped steam drum, a lower T-shaped water drum, an intermediate transverse drum, a plurality of substantially parallel water tubes connecting said T-shaped drums 95 and a plurality of inclined water tubes connecting said intermediate drum to said T-shaped drums.

In witness whereof I hereunto set my hand this 28 day of April, 1919.

JOHN P. BADENHAUSEN.
